CLAIM

The ornamental design for an automatic juicer, as shown and described.

DESCRIPTION

FIG. 1 is a front perspective view of an automatic juicer, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is an enlarged detail view of area 9 in FIG. 1;
FIG. 10 is an enlarged detail view of area 10 in FIG. 1;
FIG. 11 is an enlarged detail view of area 11 in FIG. 1;
FIG. 12 is an enlarged detail view of area 12 in FIG. 1;
FIG. 13 is an enlarged detail view of area 13 in FIG. 2;
FIG. 14 is an enlarged detail view of area 14 in FIG. 2;
FIG. 15 is an enlarged detail view of area 15 in FIG. 2; and,
FIG. 16 is an enlarged detail view of area 16 in FIG. 2.
The broken lines in the drawings illustrate the portions of the automatic juicer, which form no part of the claimed design.
The dash-dot-dash broken lines encircling the enlarged views are for annotative purposes only and form no part of the claimed design.

1 Claim, 16 Drawing Sheets
